INVENTOR

INVENTOR

UNITED STATES PATENT OFFICE.

HERBERT M. CLARK, OF OSHKOSH, WISCONSIN.

SYSTEM OF HEATING.

SPECIFICATION forming part of Letters Patent No. 549,439, dated November 5, 1895.

Application filed January 11, 1895. Serial No. 534,546. (No model.)

To all whom it may concern:

Be it known that I, HERBERT M. CLARK, a citizen of the United States, residing at Oshkosh, in the county of Winnebago and State 5 of Wisconsin, have invented certain new and useful Improvements in Systems of Heating; and I do declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 My invention relates to a system of heating factories and the like where boilers and boiler-furnaces are used.

It is well known that the smoke coming from a boiler-furnace when it passes into the 20 breeching and base of the smoke-stack is very hot and this heat is ordinarily wasted up the stack.

25 My invention provides a means of drawing or forcing the hot smoke from the breeching or smoke-door or base of the stack, as the ease may be, by forced draft or suction, forcing or drawing it through coils or flues in a heating-drum and then back into the stack, and also at the same time blowing cold air by 30 a forced blast into the drum against and around the heated flues until it becomes heated and then through conductors or pipes to different parts of the factory, where it is blown into different rooms or portions of the 35 factory for heating purposes.

I am aware that drums provided with flues through which hot smoke passes by natural draft have heretofore been used; but no forced draft similar to my invention has been 40 used, and the air to be heated has been permitted to naturally circulate between and among the flues in a natural direction from all parts of the drum without being blown or forced in any manner.

45 In my invention by means of a blower and an interior arrangement of the parts of the drum I force and compel the cold air to first strike against the smoke-flues nearest to the smoke-outlet and continue along and among 50 the flues, gradually becoming heated, until it is forced out of the drum at a point near the inlet smoke-pipe, the air being forced in an

opposite direction to that of the smoke, so that with equal force to the smoke-current and the air current the air at the outlet of 55 the drum will be approximately of the same temperature as the temperature of the smoke at the inlet.

In the accompanying drawings, Figure 1 is a vertical section of my apparatus in position 60 upon an ordinary boiler. Fig. 2 is a longitudinal section, and Fig. 3 a cross-section, of my apparatus.

Similar letters and figures refer to similar parts in each view.

65 The illustration Fig. 2 shows my invention set horizontally upon the boiler and exhausting the smoke from the stack. It can, however, be set in any convenient place contiguous to the boiler, furnace, and stack, and the 70 smoke may be taken either from the stack or from the breeching and the apparatus may be arranged either longitudinally or vertically.

In the drawings, N represents the boiler; P, the grate; O, the breeching, and F the 75 smoke-stack.

A is a cylindrical drum provided with internal heads at 2 and 3 for supporting a series of flues, as M M' M', &c.

K is a vertical partition extending from the 80 front end of the drum backward as far as shown by the dotted line b, Fig. 1. By means of an exhaust-fan D the hot smoke is drawn from the stack F through a pipe C into the chamber B, thence through the flues M M 85 into the chamber H, thence through corresponding flues M' M' into the chamber B', and through the pipe E back into the stack. In this manner there is provided a constant current of hot smoke through the chamber B, 90 the flues M M, the chamber H, the flues M' M', and the chamber B', thus thoroughly heating the drum. Then by means of the blowing-fan L cold air is forced through the pipe I into the drum around and among the 95 flues M' M', back and around the rear end of the partition K, around and among the flues M M until it becomes thoroughly heated, and then out through the pipe J and through intermediate conductors or pipes to different 100 rooms in different parts of the factory. The air is forced in a direction opposite to that of the smoke, and for this purpose either a blowing or an exhausting fan may be used. Cross-

plates *s s s* may be used, if desired, to "stagger" the current of air in order to insure its being thoroughly heated.

R is a door, which may be opened to give access to the flues for cleaning purposes, and hand-holes are provided in the front chambers B' B', through which the cinders may be removed.

In addition to the heating of the factory 10 my invention also provides a forced draft for the stack, and also acts as a spark-arrester, as it serves to extinguish any sparks or cinders from the stack.

A damper G is provided within the stack 15 between the inlet-pipe C and the outlet-pipe E, and by it the hot air from the furnace is prevented from ascending into the stack before it has been drawn around and through the drum, as hereinbefore described.

20 I do not wish to confine my invention exclusively to factories, as it may be used in any building and may be used in connection with any common smoke-pipe or chimney.

Therefore what I claim as my invention, 25 and desire to secure by Letters Patent, is—

1. In a heating apparatus the combination of a smoke stack, a drum provided with inlet and outlet for air, and inlet and outlet for products of combustion, and having heating 30 flues, a dividing partition separating the inlet and outlet for the products of combustion, and extending nearly the whole length of the hot air chamber of said drum and thereby causing the air which is to be heated, to 35 pass in a circuitous path from the air inlet to the air outlet, and in its passage come in contact with the exterior of the flues; this combination insuring the entrance of the products of combustion from the stack into said drum 40 on one side of said partition and its coming in contact with the interior of one series of the flues, and the passing off of the same on the opposite side of the partition and in contact with the interior of the other series of 45 the flues, and out into the smoke stack, while the heated air passes off through the air outlet, substantially as described.

2. In a heating apparatus the combination with a smoke stack, of a drum provided with 50 heating flues, a dividing partition in said drum separating the inlet and outlet for the products of combustion, and extending nearly the whole length of the hot air chamber of said drum, a blower adapted to draw the 55 smoke from the stack through one series of said flues and back through the other into the stack, an air inlet and outlet for said drum located respectively on opposite sides of said partition, and a blower for forcing the 60 air through said drum, substantially as described.

3. In a heating apparatus the combination with a smoke stack, of a drum provided with heating flues, a dividing partition in said

drum, separating the inlet and outlet for products of combustion and extending nearly the whole length of the hot air chamber of the said drum; independent pipes connecting the smoke stack with the drum on the opposite sides of the partition whereby the products of combustion pass forward through one series of flues and back through the other, and a damper in the smoke stack above the inlet pipe and below the outlet pipe of said drum, substantially as described. 75

4. In a heating apparatus, the combination with a smoke stack, of a drum provided with heating flues, a dividing partition in said drum separating the inlet and outlet for the products of combustion, and extending nearly 80 the whole length of the hot air chamber of the said drum, independent pipes connecting the smoke stack with the drum on opposite sides of the partition whereby the products of combustion pass forward through one series of 85 flues and back through the other, a damper in the smoke stack above the inlet pipe and below the outlet pipe of said drum, an air inlet and outlet for said drum located respectively on the opposite sides of said partition, 90 and a blower for forcing the air through said drum, substantially as described.

5. In a heating apparatus, the combination with a smoke stack, of a drum provided with heating flues, a dividing partition in said 95 drum separating the inlet and outlet for the products of combustion, and extending nearly the whole length of the hot air chamber of the said drum, independent pipes connecting the smoke stack with the drum on opposite 100 sides of the partition whereby the products of combustion pass forward through one series of flues and back through the other, a blower for drawing the products of combustion off from one side of said partition, air 105 inlet and outlet pipes located respectively on the opposite sides of said partition, and a blower for forcing the air through said pipes, substantially as described.

6. In a heating apparatus, the combination with a smoke stack, of a drum provided with heating flues, a dividing partition in said 110 drum separating the inlet and outlet for the products of combustion, and extending nearly the whole length of the hot air chamber of 115 the said drum and cross plates on each side of said partition, means for passing the contents of the smoke stack forward through one series of said flues and back through the other, and air inlet and outlet passages for 120 said drum, substantially as described.

In testimony whereof I affix my signature in presence of two witnesses.

HERBERT M. CLARK.
